COMBINED ROTATABLE MERCHANTISE SALES AND DISPLAY TABLE

John W. Holman, Wellington, Kans.

Application June 28, 1954, Serial No. 31,187

Term of patent 14 years

(Cl. D80—11)

TICK. I.

FIG. 2.

To all whom it may concern:

Be it known that I, John W. Holman, have invented a new, original, and ornamental Design for a Combined Rotatable Merchandise Sales and Display Table, of which the following is a specification, reference being had to the accompanying drawing, forming a part hereof.

Fig. 1 is a perspective view of a combined rotatable merchandise sales and display table showing my new design.

Fig. 2 is a top plane view of the design shown in Fig. 1.

I claim:

The ornamental design for a combined rotatable merchandise sales and display table, as shown.
